UNITED STATES PATENT OFFICE.

WILLIAM LESTER JONES, OF STOCKTON, CALIFORNIA

APPARATUS FOR OXIDIZING FLOUR.

No. 895,405.

Specification of Letters Patent.

Patented Aug. 4, 1908.

Application filed January 2, 1906. Serial No. 234,236.

To all whom it may concern:

Be it known that I, WILLIAM LESTER JONES, a citizen of the United States, and resident of Stockton, in the county of San Joaquin and State of California, have invented a new and useful Improvement in Apparatus for Oxidizing Flour, of which the following is a specification, reference being had to the accompanying drawings.

10 My invention relates to the art of artificially aging flour by subjecting the same to a gaseous oxidizing agent, and has for its object to use a simpler, yet efficient, process, and also provide for such purpose a more simple apparatus, than heretofore used.

15 The principle of such artificial aging-treatment consists, as is known, in bringing a small quantity of free oxygen in contact with the flour while the latter is agitated, and therefore any means by which free or nascent oxygen may be obtained and brought in contact with the flour produces the desired result. It is, however, also desirable that the means employed towards such end be as simple as possible. Since only a very small quantity of nascent oxygen is needed, electric sparking of a confined volume of air has been employed; but such means are fraught with danger in a mill. I have discovered 20 that I may obtain nascent oxygen by the use of a voltaic cell, the cathode and anode of which are electrically connected; or, preferably, by a plurality of units of such cells, the cathode and anode of each of which is electrically connected that is so that each cell 25 will constitute a unit by itself and in which the voltaic action is produced by certain acids.

30 In the practice of my invention I have found it convenient to employ a cell commercially known as a "Fuller cell", and consisting of an outer jar in which is suspended a slitted cylinder of carbon, a porous pot placed within the latter, and a bar of zinc inserted in the 35 porous pot. I partially fill the central porous pot with a weak solution of sulfuric acid—one part of the acid to forty of water; and the outer jar I partially fill with chemically pure nitric acid. These cells I place in 40 a chamber through which I force a current of air into the flour agitator-chamber.

The cell chamber I have constructed as illustrated in the drawings, in which

45 Figure 1 is a longitudinal section of such chamber, on a line z of Fig. 2, and its appur-

tenances, Fig. 2 is a plan or top view thereof, and Fig. 3 is a cross-section on line $y-y$ of preceding figures, viewing the same as pointed by the arrow z .

The chamber C is conveniently constructed of lumber and comprises a bottom 1, sides 2, 3 and ends 4, 5. I also preferably make the same of such size that I may divide it longitudinally by a removable partition 6, slidably held by its ends in vertical grooves 6¹ in the inner faces of the ends 4, 5. By this arrangement I am enabled to treat two grades of flour simultaneously, as will be further explained below.

The inlet-end has an opening 7 in which to inject a current of air from a rotary fan 8 operated by a belt and pulley 9. Such inlet end is controllable by a slide 15 having a hole 16 so that the slide may be adjusted to allow the full volume of the in-blown current of air to enter the chamber from the fan, or cut off a part thereof proportionately to the volume of nascent oxygen generated by the voltaic cells. The outlet end is made with two openings from which extend ducts 10, 11 to the flour agitator-chamber, that is, the chamber in which the ground flour is contained in an agitated state and exposed to the air impregnated with nascent oxygen.

7 The outlet openings are controlled by vertically slidable doors 12, 13 respectively. As already mentioned, the chamber C is divided into two compartments $c' c''$, and ducts 10, 11 lead therefrom into two independent agitator-chambers (not shown) in which to simultaneously oxidize two grades of flour. By closing either of the doors 12, 13 and removing the partition 6 a chamber of increased size is obtained. Under such circumstances of course the air-current would be discharged through one outlet-duct only, and the other be closed by a door dropped in front thereof. Such arrangement is convenient for treating a large quantity of flour of a single grade.

8 The chamber is proportioned to have a length of about 28 inches, width 17 inches and height of 16 inches. When so proportioned the two compartments obtained by dividing the chamber lengthwise, as mentioned, will each have a capacity for treating about 400 barrels per twenty four hours.

On the floor of each division or compartment of the chamber is placed a plurality of cells 17, and the two terminals of each cell

are electrically connected at the time operation is to be started. I use the expression "plurality" instead of battery because while the cells would act as well if connected 5 in series, yet it is necessary to renew the dilute sulfuric acid in the porous pot about once every twenty four hours, to maintain the efficiency of the cells; and therefore I prefer to arrange them as disconnected units. 10 To obtain a practically air-tight fit for the slides I line the same with cotton flannel or other suitable fabric. For the same end, the top-edge of the walls of the chamber C are faced with a like material, for the flange 15 of the cover to lie on. The chamber is provided with a hinged cover 14, and therefore allows convenient access to the voltaic cells.

While I have particularly mentioned a "Fuller cell", of course any cell may be used

capable of emitting, while in action, a gaseous compound including nascent oxygen. 20

I claim—

In an apparatus of the character described, the combination with a chamber having inlet and outlet openings and means 25 for blowing a current of air through the chamber of a voltaic battery contained in said chamber, the terminals of the battery being short-circuited, said short-circuited battery generating gaseous compounds possess- 30 ing bleaching properties.

In testimony whereof, I have hereunto affixed my signature in the presence of two witnesses.

WILLIAM LESTER JONES.
